UNITED STATES PATENT OFFICE.

GEORGE KING, OF HARTFORD, CONNECTICUT.

IMPROVEMENT IN FOLDING WASH-BENCHES.

Specification forming part of Letters Patent No. 134,149, dated December 24, 1872.

To all whom it may concern:

Be it known that I, GEORGE KING, of Hartford, Hartford county, Connecticut, have invented certain new and useful Improvements in Portable Wash-Benches, of which the following is a specification, reference being had to the accompanying drawing, in which—

The device is a bench or form which can be folded into a small compass.

The top of the form is composed of two box-halves, a a, hinged together by the hinges b b, so that they will shut together, and may be held shut by the hook c taking into an appropriate ring on the other box-half. The legs d d, united by the cross-piece d', and forming a leg-frame, so to speak, are pivoted or hinged to the under side of the table-top, so that they may fold down into the box-halves. They are held extended when desired by the rods e e taking into the staples on the inner side of the cross-pieces d' d'. These cross-pieces are set back from the inner sides of the legs so as to give space for the rods to lie under them when the leg-frames are folded down. There are handles f f attached to the box-halves, so that the whole may be readily carried by means of them when the whole is folded up into a box, as shown in Fig. 2.

I claim as my invention—

The combination of the box-halves a a hinged together, the folding leg-frames d d hinged to the box-halves, and the hooks e e, the leg-frames and hooks so attached within the box-halves as to be excluded from sight when the box-halves are closed together, the whole constructed and designed to operate substantially as described, for the purpose set forth.

GEORGE KING.
